CLOSURE PLUGS

John M. Marchyn, Merriton, Ontario, Canada, assignor to American Flange & Manufacturing Co. Inc., New York, N.Y., a corporation of Delaware

Application July 5, 1955, Serial No. 520,005

4 Claims. (Cl. 220—39)

This invention relates to closure plugs for containers and is particularly concerned with the seating of gaskets carried by the same and the relationship of the thread formation to such gasket seating.

Heretofore, in the formation of closure plugs with recessed type gasket seats for complete confining of the gasket when the plug is seated in the plug receiving member, difficulty has been encountered in the proper application of gaskets to the plugs, where such gaskets have been either square or rectangular in cross-section. Whether such gaskets have been properly applied or not, difficulty has also been encountered in some instances due to the gaskets "bunching up" in one place and being drawn out in others. However, the only commercially economical manner of producing such gaskets in the quantities required, is to slice them from extruded tubes, which necessarily results in gaskets whose cross-sections are either square or rectangular, depending on the relationship of the width of the cut to the thickness of the tube wall.

As to the plugs themselves, the preferred manner of producing them with the exactness required and in the quantities required, is by die casting, or moulding, them from suitable metals or plastic. The threads for the plugs are thus formed right on the body, during the moulding or casting. In accordance with the procedures heretofore followed for forming the dies for this purpose, the threads on the plugs have been made to commence and terminate abruptly.

Recessed gasket seat plugs, with which the invention is concerned, have outwardly extending rims around their upper ends, which form a right angle shoulder beneath them. Between that shoulder and the upper end of the threads there is an annular smooth surface on which the gasket seats. At the opposite side from the shoulder this annular surface is bordered by the upper end of the threads. Thus where that end of the threads has heretofore terminated in an abrupt end and the threads have been of the same pitch throughout, several factors have been present to interfere with proper gasket seating. This is particularly true where, due to the large numbers being produced, the gaskets are applied to the plugs by mechanical means.

One difficulty has been that where the thread approaches its termination, and thus is closest to the shoulder on the rim, the gasket is held rather tightly, whereas in the positions where the thread has departed from the rim the gasket is able to move up and down on its seat and, in this respect, be somewhat loose. This situation, in and of itself, creates no great difficulty, but where the thread comes to an abrupt end the gasket is sometimes caught between that end and the shoulder. Thus when the plug is threaded into its receiving member, the gasket, unless it slides smoothly on the receiving member, will be bunched up at this position and drawn out where it is free to move. This can cause it to kink up slightly, to catch on to the remainder of the threads, or even to be forced off its seat to at least a small extent.

2

These, and other factors, tend, in some instances, to render such closure ineffective or make it necessary to replace the gasket in order to make an effective closure. The instances are rather few and far between, but where they do occur the leakage of a substantial quantity of possibly dangerous, or inflammable, liquids can result.

An effective solution to the foregoing problems has been sought for a considerable time. One approach has been by way of attempting to form such gaskets of cross-section other than rectangular, but, besides such gaskets failing to provide a real solution to this problem, the cost of producing them is prohibitive. A more effective solution has been to coat the exterior of the gaskets with a lubricating powder or other material. Here, of course, the results are dependent upon the coating being properly and uniformly applied and remaining on the gasket during shipment of the plugs and until they are put into use. Obviously these attempts have not provided any real solution to the above problems. It has remained for such a solution to be provided by the instant invention.

The instant invention solves the problem by the provision of a special thread formation at the upper terminating end of the thread, where the same borders the basket seat. Here, instead of bringing the thread to an abrupt termination, an additional partial thread has been continued around a complete circumference, diminishing regularly as it continues around the plug periphery. In addition to the diminishing of it, the helix angle of this last thread is reduced to one-half of that of normal threads, so that, for instance, where American standard straight pipe threads would call for 11½ threads to an inch, the diminishing threads run at the rate of 23 threads to an inch. Thus the diminishing thread has one half the pitch, or twice as many threads per inch, as the regular threads. The diminishing thread, however, maintains the same thread form, that is the same side wall angularity as the regular threads.

The diminishing thread, in spite of the change in the helix angle and due to maintaining the angularity of its side, still engages, on its lower side, with the mated surface on a threaded receiving member having standard threads. More importantly, however, the reduction of the helix angle, plus the diminishing, creates a border at the lower side of the gasket seat which is parallel with the shoulder bordering the upper side of the gasket seat. In other words the line where the upper flank of the diminishing thread engages the gasket seat comes out as parallel to the shoulder opposite to it. Also, importantly, the upper surface of the diminishing thread, maintaining as it does a 30° angularity with respect to the vertical, provides an inclined leading surface all around to lead the gasket down on to its seat. Thus, even though the gaskets are rapidly and mechanically applied, they will, as they contract from their expanded condition caused by the applicator, slide down the inclined upper side of the diminishing thread and seat evenly and with uniform tension on their seats and around their circumferences. There are no obstructions to catch them or bunch or stretch them at any position as the plugs are screwed home and the inclined surface of the thread is ever present to overcome any tendency of the gasket to unseat itself.

It is accordingly a principal object of the invention to improve upon the seating of gaskets for closure plugs.

Another object is to improve upon such gasketing while leaving the threaded side wall of such plugs unobstructed.

Still another object is to modify the thread formation on such plugs to cause the same to assist in seating the gasket.

A further object is to eliminate distortions in the seat-

ing of rectangular cross-section gaskets beneath the heads of flush type closure plugs.

A still further object is to provide for the maintaining of gaskets in proper seating position during the rotation of closure plugs in the opening and closing of container openings.

Further and more detailed objects will in part be obvious and in part be pointed out as the description of the invention, taken in conjunction with the accompanying drawing proceeds.

In that drawing:

Fig. 1 is a top plan view of a plug in accordance with the invention.

Fig. 2 is a front elevation thereof looking at the plug as seen from the underside in Fig. 1.

Fig. 3 is a horizontal section taken on lines 3—3 of Fig. 2 and looking in the direction of the arrows.

Fig. 4 is an enlarged elevation of the upper threads on the plug of Fig. 1, showing one-half of the circumference of the same as viewed from the position 4—4 in Fig. 1 and laid out in the flat.

Fig. 5 is a similar view of the other half of the circumference as viewed from the position 5—5 in Fig. 1.

Fig. 6 is a vertical section taken on line 6—6 of Fig. 1 and looking in the direction of the arrows.

Fig. 7 is a similar view taken on line 7—7 of Fig. 1 and looking in the direction of the arrows.

Fig. 8 is a fragmentary vertical section taken on line 8—8 and looking in the direction of the arrows.

Fig. 9 is a fragmentary section taken on line 9—9 of Fig. 1, with the portion of the plug shown seated in its receiving seat.

The plug of the invention is of the type generally known as "flush," due to the fact that it seats down into the opening formed to receive it. In doing so it cooperates with the seat formed around the opening to confine and compress the gasket carried by it. In the present instance the plug has a cylindrical side wall 1, a bottom 2 and a head or rim 3 extending out a short distance around the top of the side wall.

The underside of the rim 3 is formed with a shoulder 4 lying in a plane at right angles to the axis of the side wall. This shoulder forms the upper border of the seat 5 for the plug gasket 6. That seat 5, itself, is in the form of a cylindrical portion of the side wall centered about the axis of the plug. The relatively small but highly effective gasket 6 is rectangular in cross-section when uncompressed. When compressed and confined, however, as illustrated in Fig. 9, it flows to fill the cavity between the opposed portions of the plug and the receiving element therefor which confines it.

As already pointed out these gaskets are formed by slicing cylindrical tubes of gasket material in planes at right angles to their axis. This is the only economical way to form effective gaskets in the quantities required for closing the many millions of containers, of the size here being considered, being produced annually. For full effectiveness, however, and for uniform foolproof application of the gaskets, whether they be applied to the plugs by hand or by machine, some means is needed to see that they seat properly against the seat 5 and up against the shoulder 4. It is not practical to form another shoulder opposite the shoulder 4 for this purpose, for that might interfere with the screwing home of the plug. Also it would interfere with the effective flowing of the gasket as illustrated in Fig. 9.

When, however, the normal threads 7 of the plug, which for closures for large containers are American standard straight pipe threads, continue up to the gasket seat with their normal pitch and terminate abruptly, the adjacent flank of the thread does little toward uniform seating of the gasket up against the shoulder 4. In fact at the position where the thread terminates, there is a gap equal in width to the pitch of the threads. These and other conditions of the prior art closures have

tended to allow a small proportion of gaskets to be improperly applied and have allowed another small proportion, whether properly applied or not, to either stretch out or bunch up and fail to form the uniformly effective seal for which they are intended. As already pointed out a variety of attempts have been made to eliminate these drawbacks but none of them, until that of the instant invention, have been successful. However, the variation in thread formation, introduced by the instant invention, solves all the prior art problems with regard to effective seating and utilization of these gaskets and does so in a simple straightforward manner. This far reaching improved result is achieved in the following manner.

First the requisite number of American standard straight pipe threads for the particular sized closure are applied as shown at 7 to the side wall 1 of the plug. As an illustration, closures for 2" size openings, for certain I.C.C. packages, have three complete threads at a pitch of 11½ threads per inch. The prior art practice would be to continue the top one of these threads just past the position which provides three complete threads and then terminate it abruptly. It has been determined, in accordance with the invention, however, that if the top thread, just beyond the position where three threads are provided, as illustrated at position 8 in Figs. 2 and 5, has its pitch halved, i.e., in this particular instance, has its pitch changed from the rate of 11½ threads per inch to the rate of 23 threads per inch and is diminished uniformly throughout a circumference, the resultant structure provides a full and complete solution to the prior art problems.

Considering this solution in detail, it is first to be appreciated that though the pitch from the position 8 on is cut in half the side wall angularity of the previous threads is maintained though diminished uniformly around the circumference. If the thread form were changed to the form or height corresponding with the change in pitch where there were accordingly twice as many threads to the inch, an abrupt shoulder would be created at the position 8 and there would be flats between this thread and the next regular one. In addition, the diminishing of such a thread would not produce the desired parallel border for the gasket seat. Where, however, the thread form of one pitch is maintained and diminished uniformly with the pitch halved, the thread will be reduced in height by one-half at the position 9, half way around the circumference from the start at 8 (Figs. 2, 3 and 5). At the opposite end of the diameter from the position 9 the diminishing thread will just disappear at 10 as it again approaches the position 8.

An important result of the uniform diminishing of the top thread, and the change of pitch, in accordance with the invention, is that the line 11, where the lead flank 12 of the diminished thread reaches the root of that thread, will lie in a plane at right angles to the axis of the threads. Thus, in this instance, the plane in which the line 11 lies will be parallel to the plane of the shoulder 4. Also, since the root of all of the threads lies on the same cylindrical surface as the gasket seat surface 5, the line 11 will thus define the lower border of the surface 5 as shown in Figs. 2 through 9. The results of this structure are that all around the plug there is a definite lower boundary to the surface 5, which boundary is parallel to the surface 4 and is the same distance therefrom as the width of the gasket 6. Furthermore the flank 12 inclines downwardly towards the line 11, all the way around the circumference. Hence, when the gasket, being of resilient rubber-like material, is expanded to position it on the seat and is then allowed to contract, its lower inner corner, as illustrated at 13 in Fig. 6, will slide down the incline 12 until it coincides with the line 11. Hence the gasket seats effectively on its seat. Moreover, as the plug is turned, there will be no gap where the gasket is unsupported from below, nor will

there be any abrupt thread termination, either or both of which acted together in the prior art constructions to hinder effective seating of the gasket. In the invention construction the gasket will, at all times, seat effectively and will do so by the built in action of the plug structure without requiring any extraneous means to assure it.

Though the illustration given calls for a closure plug of a nominal 2" diameter, where the regular standard straight pipe threads run at 11½ per inch and wherein halving the pitch and diminishing the thread uniformly while maintaining the normal thread form will produce a line 11, parallel to the shoulder 4, the same condition has been found to exist for plugs of other diameters having different thread pitches. Thus for small diameter plugs having a greater number of threads per inch, it is still merely necessary to halve the pitch of the last thread and diminish it uniformly throughout a circumference to provide a lower border line for the gasket seat 5 which will be parallel to the shoulder 4.

Illustrations of the diminishing thread at four equal positions around the circumference is seen in Figs. 6 through 9. Also, from Fig. 9, it is to be noted that though the pitch of the last thread, from the position 8 to a position 10, has been halved the continuous standard threads 14 of the receiving member for the plug mate with the lower flank 15 of the diminishing thread as it runs around the circumference. Thus the diminishing thread, rather than providing any obstruction to the screwing home of the plug, facilitates the same and adds additional thread engagement while it does so.

Though die casting and moulding have been mentioned as manufacturing methods by which formation of plugs, in accordance with the invention, is facilitated, it is, of course, to be understood that the invention is by no means limited thereby.

In forming the thread portion of the die cavities, in the dies to be used for producing plugs in accordance with the invention by casting or moulding, a standard 60° included angle cutter is used. Three of the thread cavities are cut in normal fashion to standard full thread depth. When the commencement of the fourth thread is reached the helix angle is changed to reduce the pitch to one-half and during the next 360° the cut is relieved or diminished at regular small increments. As an example, where the first threads were cut on a pitch of 11½ to the inch and the pitch was then changed to 23 to the inch, the cavity depth for the diminishing thread was reduced in equal increments of .001" for every 6° of circumference. These increments are so small that it would take substantial magnification to see that the surface varies in the straight in any manner. For all practical workable purposes it acts as a continuous diminishing surface. Also the line 11 is at least substantially parallel to the surface 4.

To eliminate the incremental changes in forming the diminishing cavity, the position of the cutting tool can be controlled by a suitable pattern or template. These dies last so long, however, and turn out large quantities of plugs so rapidly that the making up and use of patterns, or templates, is hardly warranted since the final product

is practically indistinguishable from that produced from dies where the thread cavity is diminished in increments.

Though the illustration given is for plugs whose base threads run at 11½ per inch, it is, of course, to be understood that the same procedure is followed for forming diminishing threads on plugs of other sizes having a different number of threads per inch. In all of these instances, it is, of course, to be understood that the threads being dealt with are single lead threads since standard straight pipe threads fall into this category.

Since certain changes in the above article and in carrying out the method of forming the same, which embody the invention, may be made without departing from its scope, it is intended that all matter contained in the above description, or shown in the accompanying drawing, shall be interpreted as illustrative and not in a limiting sense.

Having described my invention what I claim is new and desire to secure by Letters Patent is:

1. A die formed closure plug comprising a substantially cylindrical side wall, a base closing said side wall and an outwardly extending peripheral flange at the upper end of said side wall and a gasket seat formed on said plug immediately below said flange, said gasket seat having a pair of opposed peripheral side portions and a cylindrical bottom portion in the form of a surface extending between said side portions and joining with the same, the underside of said flange providing a shoulder forming one of said side portions of said seat, threads formed on said side wall below said gasket seat and the side portion of said gasket seat opposite said shoulder being formed with a substantially uniformly inclined surface which is the upper surface of the uppermost thread, the height of said uppermost thread diminishing substantially uniformly to the vanishing point at said surface forming the bottom of said gasket seat.
2. A closure plug as in claim 1, said uppermost thread diminishing from full thread height to the vanishing point in one full turn of the thread.
3. A closure plug as in claim 1, said uppermost thread having the same included angle between its sides as the remainder of said threads and said included angle remaining the same throughout the diminishing of said uppermost thread.
4. A closure plug as in claim 1, said uppermost thread advancing at substantially one half of the pitch of the remainder of said threads.
